UNITED STATES PATENT OFFICE.

OLIVER L. NORRELL, OF RICHMOND, VIRGINIA.

MAIL-HANDLING MEANS FOR APARTMENT HOUSES.

Application filed September 19, 1924. Serial No. 738,728.

To all whom it may concern:

Be it known that I, OLIVER L. NORRELL, a citizen of the United States, residing at Richmond, in the county of Henrico and State of Virginia, have invented new and useful Improvements in Mail-Handling Means for Apartment Houses, of which the following is a specification.

The general object of my present invention is the provision of improved means for safely and conveniently handling mail matter in apartment houses and the like—i. e., transferring mail matter from a central station at or adjacent to the ground floor to apartments on floors above the ground floor and vice versa.

The apparatus also includes means for the delivery of mail to and from apartment holders on the ground floor, as well as means for apprising the apartment holders when mail is placed in their respective depositories.

Other objects and practical advantages of the invention will be fully understood from the following description and claims when the same are read in connection with the drawings, accompanying and forming part of this specification, in which:—

Figure 1 is a front elevation illustrative of an equipment provided in accordance with my invention adjacent to the ground floor of an apartment.

Figure 2 is a front elevation of an equipment provided in accordance with my invention for an upper floor of an apartment.

Figure 3 is a detail vertical section taken in the plane indicated by the line 3—3 of Figure 1.

Figure 4 is a vertical section on the line 4—4 of Figure 2.

Figure 5 is a detail front elevation showing a depository or box of which there is one for each apartment.

Figure 6 is a section of the same taken in the plane indicated by the line 6—6 of Figure 5.

Figures 7 and 8 are views diagrammatic in character of electric connections herein-after explicitly referred to.

Similar numerals of reference designate corresponding parts in all of the views of the drawings.

The equipment of my invention includes a plurality of side by side vertical shafts 1, and it also includes, by preference stationary boxes 2 shown by dotted lines in Figure 1

for the occupants of ground floor apartments as well as boxes 3 for the occupants of apartments above the ground floor. Each of the boxes 2 and 3 referred to are provided with front doors 4, hinged at 5 and designed to be detachably secured in closed position by individual locks 6. Each of the said doors 4 is provided at 7 with a holder to receive a card 8* that bears the names of the parties resident in the apartment to which the particular box belongs. It will also be noticed that each door 4 is provided with a slot 8 for the introduction of first class mail matter and a slot 9 for the insertion of magazines and the like. The said slots 8 and 9 are normally closed by gravitational flaps 10 and 11, respectively, and the said flaps 10 and 11 are each provided with circuit closing brushes, the brush of the flap 10 being designated by 12, and the brush of the flap 11 being designated by 13, Figures 6 and 7. By virtue of this equipment it will be manifest that when either the flap 10 or the flap 11 of a particular box 3 is opened incident to the placing of mail matter in the box, the brush of the opened flap will cooperate with terminals 14 or 15 to contribute to the completion of an electric circuit such as shown in Figure 7, which circuit in addition to a source of electric energy 16 includes an electric bell 17 or any other appropriate electric signal, the said signal being intended to apprise an apartment holder of the placing of mail matter in the respective box 3 of the apartment. It will also be understood from Figure 3 that each of the boxes 3 that are movable vertically in the shafts 1 is provided with a pendent receptacle 18, the said receptacle 18 being provided with a mouth 19 and being designed for the reception of packages.

The ground floor equipment, Figures 1 and 3 includes a plurality of wall openings 20 and 21, the stationary boxes 2 being disposed in coincidence with the openings 20, and the boxes 3 being designed to be moved to and from positions in coincidence with the openings 21. All of the several openings 20 and 21, Figures 1 and 3 are designed to be controlled by a large door 22, hinged at 23 and provided at 24 with a handle in connection with a latch 25 adapted to detachably secure the door in closed position. At 26 the door 22 is provided on its inner side with protuberances which are designed to engage and close the swinging doors 4 in

the event of the letter carrier failing to close the said doors 4 after he has removed mail matter from the boxes 2 and 3, it being understood in this connection that the locks 6 5 are of the snap type.

By comparison of Figures 2, 4 and 8 it will be understood that an electric motor 27 is employed for each box 3; also, that the ends of cables 29 and 30 are connected by 10 springs 31 and 32 with the upper and lower side of each box 3, and that the cable 29 is provided at 33 with an abutment while the cable 30 is provided at 34 with a similar abutment. It will also be understood that 15 each cable 30 is carried under stationary sheaves relatively arranged as shown in Figure 3. Each cable 29 is connected to and is designed to be wound on and let off of a drum 36 to which is fixed a spur gear 27, 20 Figures 2 and 4, while each cable 30 is connected to and designed to be wound on and let off of a similar drum to which is fixed a spur gear 38. There is an electric motor 27 complementary to each pair of gears 37 and 25 38, and each electric motor 27 is provided on its armature shaft with a spur gear 39 in mesh with a spur gear 40 adapted to be meshed with the gears 37 and 38 alternately. Each gear 40 is carried by the arm 41 of an 30 angular hand lever 42, Figure 4, and each hand lever 42 is movable in a slot 43 in the front wall of a shaft 1 at one of the upper floors of the apartment house. Manifestly when the lever 42 is positioned to mesh the 35 gear 40 with the gear 37 and the motor 27 is energized the particular box 3 in connection with the gear 37 will be raised by the operation of the motor, and when the gear 40 is meshed with the gear 38, the said box 3 will 40 be lowered. At 44 and 45 the lever 42 is provided with brake strips designed to engage the drums alternately with a view to stopping rotation of the said drums. In this connection it will be understood that the 45 lever 42 appropriated to each apartment is designed to be thrown to the position shown in Figure 4 when the apartment holder desires to bring about the elevation of his particular mail box 3. It will also be understood that when the lever 42 is swung downwardly to place the gear 40 in mesh with the gear 38, the particular box 3 of the apartment holder will be lowered from the position shown in Figure 4 to the position shown 50 in Figure 3. In this connection it will be understood that when the box 3 is in the position shown in Figure 4 the said box 3 will be coincident with an opening 50 provided in the front wall of the particular shaft 1 55 adjacent to one of the upper floors of the apartment. The said opening 50 is normally closed by a gravitational slide door 51, Figure 4, the said slide door 51 being raised to the open position shown in Figure 4 as 60 the box 3 moves upwardly to position coincident with the opening 50.

By comparison of Figures 3 and 7 it will be understood that the circuit shown in Figure 7 and one of which is employed for each box 3 will be partially closed by terminals 52 on the box 3 contacting with stationary terminals 53 when the box is coincident with one of the before mentioned openings 21.

By comparison of Figures 3, 4 and 8 it will be understood that a circuit such as shown in Figure 8 and connected with the wires 60 and 61 of a main circuit is provided in conjunction with each electric motor 27 and the box 3 complementary to the said electric motor 27. Each of said circuits will be understood as including spaced terminals 62 adapted to be electrically connected by a conductor 63 on the door 22 when the door 22 is closed, this provision being made in order to prevent any apartment holder from bringing about the movement upward of his respective box 3 until after the door 22 is closed. It will also be understood that each of the said circuits complementary to a box 3 and its electric motor 27 includes spaced terminals 70 and a conductive lever 71, spaced terminals 72 and a conductive lever 73 and spaced terminals 74 adjacent to the levers 42 which is provided with conductive means 42^x.

When each box 3 is lowered and the stop 34 contacts with the lever 71, the lever 71 will be moved against the action of its spring 80 out of contact with the terminals 70, and consequently the electric circuit including the motor complementary to the particular box 3 will be interrupted and downward movement of the particular box 3 will be stopped. On the upward movement of the particular box 3 the stop 33 on the cable 29 by acting against the lever 73 will move said lever 73 out of contact with the terminals 72, and consequently the upward movement of the box 3 will be stopped when said box 3 is coincident with the opening 50 in the shaft wall, Figure 4. When the lever 42 is in connection with the terminals 74 the box 3 will be lowered, while when said lever 42 is in connection with the other pair of terminals adjacent to the lever 42, the box 3 will be raised.

By virtue of the spring connections between the cables 29 and 30, on the one hand, and the particular box 3, on the other, the completion of each upward and downward movement of each box 3 will obviously be cushioned. In this connection it will be understood that as each box 3 becomes coincident with its respective opening 50 the box 3 will bring up against stationary stops 90, Figure 4.

It will be apparent from the foregoing that certain of the circuit making and breaking provisions of my improvement preclude elevation of any one of the boxes 3 by manipulation of the lever 42 until the door 22 is closed by the letter carrier; also, that other of the circuit making and breaking provisions assure the stoppage of the motor 27 of each box 3 when the latter reaches the ends of its upward and downward traverses.

It will further be appreciated that mail is safe-guarded en route between the ground floor stations and the upper floors and vice versa, an important factor in this connection being the notification to a box holder of the opening of the door 4 of his respective box by a carrier for the placing of mail in the box.

20 I have specifically described the preferred embodiment of my invention in order to impart an exact understanding of the said embodiment. I do not desire, however, to be understood as confining myself to the construction and relative arrangement of parts as disclosed inasmuch as the scope of my invention is defined by my appended claims within which changes may be made without departure from my invention.

30 Having described my invention, what I claim and desire to secure by Letters-Patent, is:—

35 1. In mail handling equipment for apartment houses, shafts extending from a central station at the ground floor to upper floors and having openings at said points, boxes movable in said shafts, and adapted to register with said openings, means for so moving the boxes, and vertically-movable 40 gravitational doors for closing the upper openings, said doors being raised to open position by the upward movement of their respective boxes.

45 2. In mail handling equipment for apartment houses, shafts extending from a central station at the ground floor to upper floors and having openings at said points, boxes movable in said shafts, and adapted to register with said openings, a door controlling access to the several boxes at the ground floor and electro-mechanical means for raising and lowering the boxes and including controls one for each box and box holder, and also including circuit makers and 50 breakers controlled by said door whereby no box can be moved until the door is closed.

55 3. In mail handling equipment for apartment houses, shafts extending from a central station at the ground floor to upper floors and having openings at said points, boxes movable in said shafts, and adapted to register with said openings, and having doors, means for raising the boxes, and electro-mechanical signals one for each box 60 and box holder and including a circuit

maker and breaker controlled by the box door and adapted to close a normally open circuit and actuate the signal when the door is opened for the placing of mail in the box.

70 4. In mail handling equipment for apartment houses, shafts extending from a central station at the ground floor to upper floors and having openings at said points, boxes movable in said shafts and adapted to register with said openings, said boxes having doors, electro-mechanical signals one for each box and box holder and including a circuit maker and breaker controlled by the box door and adapted to close a normally open circuit and actuate the signal when the door is opened for the placing of mail in the box, a door controlling access to the several boxes at the ground floor, and electro-mechanical means for raising and lowering the boxes and including controls one for each box and box holder and also including circuit makers and breakers controlled by the last-named door whereby no box can be moved until said door is closed.

75 5. In mail handling equipment for apartment houses, shafts extending from a central station at the ground floor to upper floors and having openings at said points, boxes movable in said shafts and adapted to register with said openings, said boxes having doors, electro-mechanical signals one for each box and box holder and including a circuit maker and breaker controlled by the box door and adapted to close a normally open circuit and actuate the signal when the door is opened for the placing of mail in the box, a door controlling access to the several boxes at the ground floor, and electro-mechanical means for raising and lowering the boxes and including controls one for each box and box holder and also including circuit makers and breakers controlled by the last-named door whereby no box can be moved until said door is closed; the said upper openings of the shafts being provided with vertically movable gravitational doors, and the said doors being relatively arranged to be raised to open position by the box complementary to the door as said box moves upwardly into coincidence with its respective upper opening.

80 6. In mail handling equipment for apartment houses, shafts extending from a central station at the ground floor to upper floors and having openings at said points, boxes movable in said shafts and adapted to register with said openings, a door controlling access to the several boxes at the ground floor, and electro-mechanical means for raising and lowering the boxes and including controls one for each box and box holder, and also including circuit breakers for stopping each box when it reaches a position coincident with either of its openings,

- and further including circuit makers and breakers controlled by the said door whereby no box can be raised until said door is closed.
- 5 7. In a mail handling equipment for apartment houses, shafts extending from a central station at the ground floor to upper floors and having openings at said points, boxes movable in said shafts and adapted
- 10 to register with said openings, outwardly opening doors complementary to said boxes, a door controlling access to the several boxes
- at the ground floor and having protuberances one for each box door to close the same; and electro-mechanical means for 15 raising and lowering the boxes and including controls one for each box and box holder and also including circuit makers and breakers controlled by the last-named door whereby no box can be raised until said 20 last-named door is closed.

In testimony whereof I affix my signature.

OLIVER L. NORRELL.
